UNITED STATES PATENT OFFICE.

EDWIN O. WALKER, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SELECTOR SWITCH.

Application filed May 11, 1923, Serial No. 638,152. Renewed January 20, 1926.

The present invention relates in general to selector switches for automatic telephone systems, but is especially concerned with improved circuit arrangements for use in controlling the trunk or automatic selecting operation of automatic switches of the step by step type usually used in automatic telephone systems; and the object of the invention is to provide controlling circuits which enable the trunk or automatic selecting operation of such switches to take place at a maximum speed, while maintaining the present degree of accuracy of operation so essential to the success of automatic telephone systems.

In order to illustrate the invention it will be assumed that the well known Strowger switch structure is to be used, although it should be understood that the invention may be equally well incorporated in any type of step by step switch.

In the drawing, comprising but a single sheet, Fig. 1 shows a circuit diagram of a selector wired in accordance with the invention; while Figs. 2 and 3 show modifications which may be substituted for certain of the controlling circuits of Fig. 1.

Referring to Fig. 1, the selector as shown has its conductors 20, 21 and 22 terminating in bank contacts of any approved type of trunk selecting switch, and is adapted to be controlled over the conductors 20 and 22 by operating impulses transmitted by a calling subscriber in well known manner to position the wipers 23, 24 and 25 opposite a desired group of bank contacts from which extend trunk lines terminating in other selector or connector switches, depending upon the capacity of the system.

Since Figs. 2 and 3 merely show modifications of certain of the controlling circuits of Fig. 1, a detailed description of these figures will be postponed until a detailed description of Fig. 1 has been given, after which the application of the modifications will be more easily made clear.

Now in order to explain the invention it will be assumed that a calling subscriber

wishes to extend a connection in an automatic telephone system in which switches such as that shown in Fig. 1 are used. Upon removal of the receiver at the calling station the individual line or trunk selecting switch seizes an outgoing selector switch. Assuming the selector seized to be the one shown in Fig. 1, a circuit will be completed for the line relay 2. This circuit may be traced from ground, lower winding of relay 2, resting contact of armature 27 and said armature, conductor 22, bank contact 12, thru the lower conductor of the line switch (not shown) out over the calling line equipment, through the upper conductor of the line switch, (not shown) bank contact 10, trunk conductor 20, armature 26 and its resting contact, and the upper winding of the line relay 2 to battery. The operation of line relay 2 completes a circuit for the release relay 4, which also operates to ground the release trunk 21, to open a point in the operating circuit of the release magnet 7, to close a point in the operating circuit of the rotary magnet 5, and to prepare an operating circuit for the usual series relay 6 and vertical magnet 3.

The calling subscriber now operates his calling device in accordance with the first digit of the desired number. A series of interruptions is thereby produced in the circuit of line relay 2, causing a corresponding series of deenergizations of the said relay, which at each deenergization sends a current impulse thru the slow acting relay 6 and the vertical magnet 3 to battery. By the operation of the vertical magnet the switch shaft is raised step by step until the wipers 23, 24 and 25 stand opposite the bank level in which are terminated the particular group of trunk lines desired. As previously stated these trunks may extend to second selectors or to connectors depending upon the capacity of the exchange. The slow acting relay 6 is energized in series with the vertical magnet, retaining its armature attracted throughout the vertical movement of the switch, and upon the first vertical

step the off normal springs 14 close a point in the operating circuit of the switching thru relay 8. At the end of the vertical movement of the switch the slow relay 6 restores its armature, which causes a momentary circuit to be completed for the rotary magnet 5. This circuit may be traced from the grounded release trunk conductor 21, off normal springs 14, armature of relay 6 and its working contact, thru the break spring 29, and the winding of the rotary magnet to battery. This circuit of course is of only momentary duration, as it is opened as soon as the relay 6 has fully retracted its armature, but is of sufficient duration to permit the rotary magnet to close a locking circuit for itself at its springs 17, which are closed at the beginning of the stroke of the armature. This locking circuit is maintained until the rotary magnet has rotated the shaft one step, to position the wipers 23, 24 and 25 on the first bank contacts of the selected group, at which time the locking circuit is broken at interrupter springs 16, opened near the end of the stroke, and the rotary magnet retracts its armature. The rotary magnet, in restoring its armature, necessarily again closes the locking circuit at interrupter springs 16 before opening the locking springs 17, but the spring used for restoring the armature of the rotary magnet is adjusted so stiff that when the circuit is opened at interrupter springs 16, the restoring action of the armature is sufficiently fast to insure its complete retraction and the opening of the locking springs 17 before the magnet has time to again become saturated by the circuit closed through the interrupter springs.

40 The operation now depends upon whether the test contact with which the test wiper 24 is in engagement is busy or is not busy. If the test contact is busy it will have a ground potential upon it, and a circuit will again be completed for operating the rotary magnet. This circuit may be traced from a grounded busy contact such as 32, wiper 24, armature 15 and its resting contact, armature 39 and its working contact, interrupter springs 16 and the winding of magnet 5 to battery. It will be clear that as long as the wiper 24 engages grounded or busy bank contacts that the rotary magnet will continue to vibrate, and at each energization will lock itself up at springs 17 until its wipers have entirely disengaged themselves from the bank contacts of a busy trunk and have been positioned on the subsequent bank contacts to be tested, at which time interrupter contacts 16 will be opened.

45 It will be noted that when the slow acting relay 6 retracted its armature to close the initial operating circuit of the rotary magnet, that ground was also extended from the release trunk conductor 21, thru off normal

50 springs 14, armature of relay 6 and its resting contact to the winding of switching thru relay 8. Furthermore when the rotary magnet 5 energized it also extended ground from its armature 17 and its working contact to the opposite terminal of the winding of relay 8. It will be seen therefore that this relay is always short circuited while the wipers are being moved from one set of contacts to another, and by the grounded or busy test contact while the magnet is deenergizing. If however the wiper 24 is positioned on a test contact of an idle trunk, as soon as the locking circuit is broken at springs 17 there will be no ground present on this contact, and the switching thru relay will no longer be short circuited. This relay will now energize over a circuit extending from battery, winding of magnet 5, interrupter springs 16, winding of the switching relay 8, resting contact and armature of slow relay 6, off normal springs 14 to the grounded release trunk conductor 21. Owing to the high resistance of the switching relay 8, the rotary magnet is not energized by current flow in the above circuit. Relay 8 upon energizing, disconnects the trunk conductors 20 and 21 from the windings of the line relay 2 and extends them by way of armatures 26 and 27 and their working contacts, line wipers 23 and 25, bank contacts 31 and 33 to the extended idle trunk conductors 34 and 36. The deenergization of line relay 2 opens the circuit of slow release relay 4, but before this relay retracts its armature to remove ground from the release trunk 21, relays in the switch ahead have operated in well known manner to feed holding ground back over conductor 35, bank contact 32, wiper 24, armature 15 and its working contact, to the winding of relay 8, and also back thru springs 14 to conductor 21 to maintain ground on the holding circuit of the subscriber's line switch (not shown) as is the usual practice.

55 The release of the selector is brought about in the usual manner, that is, the calling subscriber upon replacing his receiver causes ground to be removed from conductor 35, whereupon the switching relay 8 deenergizes and closes a circuit for the release magnet 7 at armature 28. It should be noted that the rotary magnet is disconnected from the private wiper 24 at armature 39 during the restoring movement so that it will not be affected by busy contacts engaged at this time. When the switch is fully restored the release circuit is opened at off normal springs 9.

60 The description of the operation of the selector as shown in Fig. 1 having been completed, the operation of the modification of the rotary magnet controlling circuit shown in Fig. 2 will now be described. It should be noted that in the modifications where

part of the relays, conductors, etc., are the same as shown in Fig. 1, the same reference numerals (with exponents) have been applied.

3 The operation of the selector of Fig. 1 modified according to Fig. 2 will be the same as previously described so far as the group selection is concerned. However, with the circuits modified, when the switch takes 10 one step in its group selecting movement, the off normal springs 14' close, completing a circuit for the slow relay 18, from ground, winding of relay 18, working contact and armature of relay 6' (this relay being energized in series with the vertical magnet in the manner previously described) off normal springs 14', and the winding of rotary magnet 5' to battery. The relay 18 will energize to apply ground to the resting contact of 15 the armature of relay 6' and to interrupter springs 16' for purposes which will be subsequently made clear. Owing to the high resistance of relay 18, the rotary magnet is not energized by current flow in the above 20 circuit.

At the end of the vertical movement of the switch the slow acting series relay 6' will deenergize, and in so doing opens the energizing circuit of slow release relay 18. 25 An initial operating circuit for the rotary magnet 5' is now completed. This circuit extends from grounded working contact and armature of relay 18, resting contact and armature of relay 6', off normal springs 14', and the winding of the rotary magnet to 30 battery. The magnet 5' operates to position the wipers corresponding to wipers 23, 24 and 25 into engagement with the first contacts of the selected trunk group. The adjustment of the slow relay 18 may be such 35 that the circuit of magnet 5' is maintained by it, either, only until the locking springs 17' are closed, or until the magnet has been fully operated, in effect the resultant operation will be the same. Assuming the first 40 trunk of the group to be busy, as soon as the interrupter and locking springs 16' and 17' of magnet 5' restore a new operating circuit will be completed, from the grounded wiper 24', armature 15' and its resting contact, armature 39' and its working contact, 45 interrupter springs 16', resting contact and armature of relay 6', off normal springs 14' and the winding of the rotary magnet 5' to 50 battery. From this point on the rotary movement of the wipers corresponding to wipers 23, 24, and 25 and the switching thru on the first idle trunk is substantially the same as previously described.

55 It will now be assumed that the selector of Fig. 1 is equipped with a rotary magnet controlling circuit as shown in the modification Fig. 3. In this modification instead of using a slow relay, such as the relay 18, for completing the initial operating circuit of

the rotary magnet, a pair of rotary off normal springs 13 are used.

As soon as the vertical magnet gets its first operating impulse the slow relay 6' opens a point in the operating circuit of the 70 rotary magnet, and as soon as the switch has taken one complete vertical step a point in the rotary magnet circuit is closed by off normal springs 14'. At the end of the vertical, or group selecting movement of the 75 switch relay 6' deenergizes and completes an initial operating circuit for the rotary magnet 5', from grounded release trunk conductor 21', rotary off normal springs 13, armature 39' of relay 4' and its working contact, armature of relay 6' and its resting contact, interrupter springs 16', vertical off normal springs 14', and the winding of the rotary magnet 5' to battery. As soon as the 80 rotary magnet has taken a complete step to 85 properly position the wipers 23, 24 and 25 on the bank contacts of the first trunk of the selected group the rotary off normal springs are opened. The subsequent operating circuit of magnet 5' extends from wiper 24', 90 armature 15' and its resting contact, armature 39' and its working contact, armature of relay 6' and its resting contact, interrupter springs 16', vertical off normal springs, 14', and the winding of the rotary 95 magnet 5' to battery. The remainder of the operation is substantially the same as previously described and therefore need not be repeated.

Having described the invention, what is 100 considered to be new and is desired to have protected by Letters Patent will be pointed out in the appended claims.

What is claimed is:

1. In an automatic switch, a stepping 105 magnet, a plurality of operating circuits for said magnet, a locking circuit for said magnet, means for closing one of said operating circuits to cause the initial energization of said magnet, means responsive to a partial energization of said magnet for closing said locking circuit, means responsive to the complete energization of said magnet for opening said locking circuit to deenergize said magnet, and means effective only after said locking circuit has been opened for completing a second operation circuit for said magnet to continue the stepping action of the magnet. 115

2. In an automatic switch having wipers 120 and sets of bank contacts adapted to be engaged thereby, a motor magnet operatively connected to said wipers for moving said wipers into engagement with any set of said bank contacts, an energizing circuit for said magnet to initiate the wiper positioning movement of said magnet, a locking circuit for said magnet closed in response to a partial energization thereof to insure the proper 125 positioning of said wipers independent of 130

said first operating circuit, and means for opening said locking circuit after said wipers have been properly positioned.

3. In an automatic hunting switch, a stepping magnet, a test wiper, a circuit for said magnet including said wiper, a self locking circuit for said magnet closed at the beginning of the energization thereof, and contacts for opening both circuits as soon as the magnet is fully energized.

4. In an automatic hunting switch, a stepping magnet, a test wiper, an armature on said magnet for advancing said wiper when the same is attracted, a circuit for said magnet including said wiper, a locking circuit for said magnet excluding said wiper, means controlled by said armature for closing said locking circuit at the beginning of the movement of the armature, and means for opening both circuits when the armature is fully attracted.

5. In an automatic switch, wipers, sets of bank contacts accessible to said wipers, a magnet for moving said wipers into successive engagement with said sets of bank contacts, an initial energizing circuit for said magnet, a locking circuit for said magnet, means for closing said first circuit for initially operating said magnet to cause said wipers to be moved into engagement with one set of said bank contacts, means for closing said locking circuit until the wipers have been accurately positioned on said set of contacts, and another operating circuit including one of said wipers and a bank contact for initiating the reoperation of said magnet.

6. In a selector switch, primary and secondary operating magnets, a "change-over" relay energized in circuit with said primary magnet, contacts on said relay effective when the same deenergizes for transmitting a momentary impulse to said secondary magnet to partially energize the same, and a locking circuit for completely energizing said secondary magnet.

7. In a selector switch, primary and secondary operating magnets, a "change-over" relay energized in circuit with said primary magnet, contacts on said relay effective when the same deenergizes for transmitting a momentary impulse to said secondary magnet to partially energize the same, contacts operated by said secondary magnet responsive to its partial energization, and a circuit including said last mentioned contacts for fully energizing said secondary magnet.

8. In combination, an electromagnet having two circuits, means for partially operating said magnet over the first circuit to close the second circuit, means responsive to a further operation of said magnet for restoring said magnet, and means moved in a step by step manner by successive operations of said magnet.

9. In combination, an electromagnet carry-

ing a vibratory armature, a pair of contacts opened by said armature when it reaches its normal position, a second pair of contacts opened by said magnet armature when it reaches its operated position, and a circuit for said magnet through said two pairs of contacts in series.

10. In combination, an electromagnet carrying a vibratory armature, a pair of contacts operated by said armature when it reaches its normal position, a second pair of contacts operated by said armature when it reaches its operated position, a circuit for said magnet controlled jointly by said two pairs of contacts, and another circuit for said magnet including one pair of contacts and excluding the other pair.

11. In combination, an electromagnet carrying a vibratory armature, a pair of contacts opened by said armature when it reaches its normal position, a second pair of contacts opened by said magnet armature when it reaches its operated position, a circuit for said magnet through said two pairs of contacts in series, and another circuit for said magnet including the second pair of contacts and excluding the first pair of contacts.

12. In combination, an electromagnet carrying an armature, a pair of contacts open when said armature is in its normal position, a second pair of contacts opened by said magnet armature in its operated position, a circuit for said magnet controlled jointly by said two pairs of contacts, and an initial energizing circuit for said magnet controlled by only one pair of said contacts.

13. The combination with an automatic switch having a stepping magnet operated directly through a test wiper, of means made effective by a partial operation of said stepping magnet through said test wiper for fully operating said magnet independent of said test wiper, and means made effective by full operation of said stepping magnet for bringing about its restoration.

14. In combination, an electromagnet, means moved in a step by step manner from one position to another position by successive operations of said magnet, means for establishing an operating circuit for said magnet, and means controlled by said magnet upon its initial energization to first complete a locking circuit for itself and then to cause the deenergization of the magnet.

15. In combination, an electromagnet, means moved in a step by step manner from one position to another position by successive operations of said magnet, means for partially energizing said magnet, and means controlled by said magnet as soon as it becomes partially energized to first fully energize the same and then to deenergize it.

16. In an electrical control system where-
in there is provided an electromagnet and

means moved in a step by step manner from one position to another by successive operations of said magnet, and means effective under predetermined conditions to restore 5 said means to its initial position, means for partially energizing said magnet and means controlled by said magnet as soon as the

magnet becomes partially energized to first fully energize the magnet and then to de-energize it.

In witness whereof, I hereunto subscribe my name this 7th day of May, A. D., 1923.

EDWIN O. WALKER.
